UNITED STATES PATENT OFFICE.

SAMUEL CROCKER, OF OKLAHOMA, OKLAHOMA.

HAT.

1,175,717.

Specification of Letters Patent. Patented Mar. 14, 1916.

Application filed October 17, 1914. Serial No. 867,112.

To all whom it may concern:

Be it known that I, SAMUEL CROCKER, a citizen of the United States, residing at Oklahoma city, in the county of Oklahoma and State of Oklahoma, have invented a new and useful Hat, of which the following is a specification.

The device forming the subject matter of this application is a hat and one object of the present invention is to provide novel means whereby a single element may be employed as the brim of the hat and as a deck, which, being spaced from the top of the crown of the hat, affords and permits a circulation of air above the top of the crown.

The invention aims to improve structurally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the accompanying drawings: Figure 1 shows one form of the invention in side elevation; Fig. 2 is a longitudinal section of the structure shown in Fig. 1; Fig. 3 is a longitudinal section showing a modified form of the invention.

The hat herein disclosed comprises a crown 1 including a side wall 2 and a top 3, the side wall 2 and the top 3 being devoid of openings, so that dust cannot find its way within the crown 1 onto the head of the wearer.

The crown may be circumscribed by an outer band or ribbon 4, or may be trimmed in any other desired manner. Located within the crown 1 is the ordinary sweat-band 5. The lining is shown at 6 and extends down between the sweat-band and the side walls 2 of the crown, the lining, in hats of this type ordinarily being made of netting. Extended across the inner face of the top 3 of the hat longitudinally thereof, and superposed upon the lining 6 is a comparatively narrow ribbon or strip 7 commonly found in hats and at times inscribed with the name of the wearer or the name of the maker. The rib-

bon or strip 7 ordinarily is fashioned from some comparatively strong textile material.

Superposed upon the top 3 of the crown 1 are end blocks 8. Side blocks 9 are provided, and resting upon the top 3 at its center is a central block 10. These blocks 10-9-8 act as supports, upholding a deck 11, the periphery of which projects as shown at 12 beyond the periphery of the crown. The projecting portion 12 of the deck 11 may be of any desired extent and in this connection it is to be understood that the portion 12 of the deck is to project far enough to shield the head and face of the wearer from the rays of the sun and to render unnecessary the carrying of an umbrella or parasol. The deck 11 may be secured to the spacing blocks in any desired manner and the latter may be secured as found conveniently to the top 3 of the crown 1. If desired, fasteners 14 may be passed downwardly through the top 3 and through the respective spacing blocks. Those fasteners 14 which pass through the end blocks 8 and through the central block 10 are clenched against the band or ribbon 7. The band or ribbon 7, therefore, acts as a washer or protector, preventing the top 3 of the crown from being broken or distorted when the fasteners are clenched as at 15.

It is to be observed that in a hat constructed as shown in Fig. 1, the air will circulate freely between the deck 1 and the top 3 of the hat, the head of the wearer being maintained in a comparatively cool condition. Owing to the fact that the crown 1 is imperforate, there is no opportunity for dust to find its way into the crown and onto the head of the wearer. It will be understood of course that the deck 11 may project to any desired extent beyond the periphery of the crown and that the entire structure may be trimmed as found desirable, in order to adapt it for wear by either men or women.

In Fig. 3 of the drawings, a modified form of the invention is shown. The crown of the hat remains precisely as described hereinbefore, and therefore, the numerals previously employed are applied to Fig. 3 to designate the constituent parts of the crown. The deck, however, is a composite structure and comprises an annular rim 16 having an opening 17 of the same size as the crown. Overlaid upon the rim 16 and closing the opening 17 is a cover plate 19. The several

facing blocks denoted generally by the reference character 18 are supported on the top of the crown and in turn support the cover plate 19. These spacing blocks 18 fit against the edges of the opening 17. Therefore, the cover plate 19 and the rim 16 cannot move transversely, these parts preferably being glued or cemented together at the point 21 where they overlap. The fasteners 20 may be employed as before, the fasteners passing through the cover plate 19. The hat shown in Fig. 3 differs from the hat shown in Figs. 1 and 2 only in regard to the deck, the deck in Fig. 3 being a two-part structure, whereas in Figs. 1 and 2 the deck is a unitary element.

The specific advantages attributed to the structure shown in Fig. 3 arise out of the fact that the structure shown in Fig. 3 may be built up out of hats which a manufacturer may have in stock. Thus, a manufacturer may sever the brim of a hat from the crown, close to the crown, the brim thereupon becoming the annular rim 16 having an opening 17. The rim thus formed is used in connection with the same crown whereupon the rim was cut. In order to provide the cover plate 19, the top is cut out of the crown of a hat of a slightly larger size. Thus it will be seen that the hat shown in Fig. 3 may be built up out of stock hats of standard form, it being unnecessary to weave or fashion a single, unbroken plate to form the deck 11 shown in Figs. 1 and 2.

Having thus described the invention, what is claimed is:—

1. In a hat, a crown comprising an imper-

forate side wall and an imperforate top; a deck spaced from the top and projecting peripherally beyond the top; and spacers interposed between the top and the deck.

40

2. In a hat, a crown comprising an imperforate side wall and an imperforate top; a deck spaced from the top and projecting peripherally beyond the top; spacers interposed between the top and the deck; and fastening devices engaged with the deck, the spacers and the top.

45

3. In a hat, a crown; a rim located above the crown and having an opening of the same peripheral contour as the crown; a cover plate superposed upon the rim and closing the opening, the cover plate being peripherally secured to the rim; and spacers projecting upwardly from the crown, the spacers abutting against the cover plate and against the inner edge of the rim.

50

4. In a hat, a crown comprising an imperforate side wall and an imperforate top; spacers mounted on the top; and an imperforate deck supported on the spacers, to permit a circulation of air between the deck and the top, the imperforate crown serving to prevent the entrance of dust onto the head of the wearer.

55

In testimony that I claim the foregoing as my own, I have hereto affixed my signature in the presence of two witnesses.

SAMUEL CROCKER.
